TOE SEPARATING DEVICE

Stella Maynier, Forest Hills, N. Y.

Application July 31, 1947, Serial No. 765,058

5 Claims. (Cl. 128—81)

1

The present invention is directed to a device for separating the toes of the human foot for various purposes, such as for medication, treatment or the like.

In many cases it becomes desirable to provide a device for separating the toes of a person for various purposes, as for example, to prevent irritation between the toes, to treat infections of the feet and to apply polish or lacquer to the toe nails. For this purpose, various toe separator devices have been produced, as for example, in one such device there was a base member and formed integrally therewith were four upstanding members intended to enter the spaces between the toes. Such upstanding members were of various constructions but in all cases they were firmly secured to the base member and were of relatively impervious hard material. As a result, they were extremely uncomfortable for the wearer and they tended to compress the toes out of shape. Such separators were made according to a standard pattern and since the spacing and size of the toes of different individuals vary greatly and the depth of the spaces between the toes are of widely varying sizes, such separators can be worn with comfort by only a very few persons.

The present invention is intended and adapted to overcome the difficulties and disadvantages inherent in prior structures of the type described, it being among the objects of the present invention to provide a toe separating device which is convenient to use and which is readily adapted for application to various types and sizes of feet.

It is also among the objects of the present invention to provide a toe separating device wherein the separator elements are made of a soft spongy material, which are so formed that they may be readily inserted between the toes and not cause any discomfort to the wearer. It is further among the objects of the present invention to provide a device of the type described wherein the separator elements are formed separate from the base on which they are mounted and are so connected that relative movement of the separators with respect to each other and with the mounting thereof is obtained.

In the accompanying drawing constituting a part hereof, in which like reference characters indicate like parts,

Fig. 1 is a top plan view of the front portion of a foot, showing the toe separating device of the present invention in position;

Fig. 2 is a vertical cross-sectional view of the device shown in Fig. 1 detached from the foot of the user;

2

Fig. 3 is a fragmentary vertical cross-sectional view taken along the line 3—3 of Fig. 1 and illustrating one method of mounting the toe separator elements to the base;

Fig. 4 is an enlarged fragmentary view of a modified form of structure illustrating a different method for mounting the separator elements on the base, and

Fig. 5 is a side view of a modification thereof.

10 There is provided a base 1 which is a flat piece of relatively soft material such as sponge rubber, made to approximately resemble the outline of the foot of the user. Cemented to the bottom of base 1 is a thin flexible sheet of impervious material 2, said material being relatively tough and acting as a support for the relatively soft base 1. The front part 3 of base 1 has the separator elements thereon and the toes of the foot 4 are adjacent to said edge when the device is in use.

15 20 Mounted on base 1 are four upright separator elements 5, each of which is adapted to enter into spaces 6 between toes 7 of the foot. The central portions 8 of each of separator elements 5 are concave so that when viewed from the end as in Fig. 2, said elements are of approximately hour-glass form. The purpose of such shape is to conveniently fit into spaces 6 and to conform with the general shape of the sides of the toes. Elements 5 are formed of highly porous spongy ma-

25 30 terial such as soft spongy rubber and the material is such that it is readily deformed to a large degree by relatively light pressures such as would be exerted by the sides of the toes. Because of this, even though the shape of elements 5 does not exactly conform with the shape of the toes or the size of the space between them, the elements by the light pressure of the adjacent toes will readily become deformed so as to accommodate themselves without discomfort for the user.

35 40 Elements 5 as shown in Fig. 3 are mounted by means of elastic threads, cords or the like 9, one of which is threaded through a central vertical opening in each separator 5, through a suitably placed opening in base 1 and tied together as shown at 10 below element 2. The upper end of threads 9 form a loop at 11 at the top of separator 5, thereby holding each separator in proper relationship to the base.

45 50 In operation the device is placed on the foot, with the separators 5, between the toes, as shown in Fig. 1. Because of the sponginess of elements 5, they will accommodate themselves to the form of the toes and the spaces therebetween. Due to the elasticity of threads 9, elements 5 will move relative to each other and to the base and find a

proper position with respect to space 6. In actual use, the device is quite comfortable even though it is worn for a considerable length of time.

In Fig. 4, there is shown a modification of the mounting means wherein elements 5 are of a somewhat different shape in that the upper edges 12 thereof are rounded and made smaller than the upper edge of the same elements shown in Figs. 1 to 3, thereby exposing the toe nails so that lacquer or polish may be applied thereto. Cemented to the bottom of element 5 of Fig. 4 is a tough flexible sheet 13, similar to sheet 2. An elastic cord, thread, band or the like 14 is threaded through sheet 2, base 1 and sheet 13 and the ends 15 thereof tied in a knot which lies between element 5 and base 1. By reason of the toughness of sheets 2 and 13, the anchorage of thread 14 is firm and secure. The exposed loop of thread 14 at the bottom of base 1 is hardly visible and the knot 15 is concealed at all times, thereby providing a neat appearing article.

Although the invention has been described setting forth two specific embodiments thereof, said embodiments are intended to illustrate the invention and not to limit the same as numerous variations in the details of construction may be made within the principles herein set forth. For instance, base 1 need not be, as shown in Fig. 1, of such size and shape as to cover the entire sole of the foot but may be made smaller and the shape thereof may be different from that shown. It is merely necessary that there be provided a base of sufficient size as to carry the separator elements and so that the edges thereof do not press into the sole of the foot or toes to cause discomfort to the user. Sponge rubber is not necessary for the base but other flexible materials such as absorbent fiber, felt, leather or the like may be used. Separators 5 may be made of various forms although it is preferable that the thickness at the center be less than the thickness at the top and bottom.

The device of the present invention may be incorporated into shoes, such as the Grecian sandal. Such a modification is shown in Fig. 5. The base 1, having separators 5 as above described, has an ankle band 16 of suitable character, which band may be of elastic material to snap about the ankle or may be of fabric, leather or the like and be open with a buckle or equivalent means for holding the same about the ankle. One or more rear straps 17 extend from the rear of the base 1 to the rear of band 16, and a plurality of front straps 18 extend from separators 5, to the front of band 16. Said band may be ornamented or jeweled and said straps may also be suitably decorated. Such a sandal may be worn for long periods of time as a corrective for the form of the toes.

It is also possible to utilize the device as footwear for adults and for children. In the latter case, it will keep the child's toes in the proper position so that they will not become deformed, as would be the case with improperly fitted shoes. My new device may be adopted to be worn within ordinary shoes for its beneficial effects. In the appended claims, it is intended to protect the device whether it is a separate unit or is incorporated in other footwear, such as shoes or sandals.

In place of individual threads 9 for each of the separators, one may use a single thread and pass the same through all four separators of a unit. For instance, it may be threaded through a needle, which is passed up and down through each separator from big toe to little toe, and the

two ends of the thread knotted on the underside of the base. While rubber is the preferred material for the separators, other substances having similar properties may be substituted for the same, such as synthetic rubber and plastics. Also, such separators instead of being made of uniform texture throughout may be hollow in the center and may, for example, be made of thin plastic material molded to the desired forms and sizes.

The means for mounting the separators on the base may be quite different from that shown and the elastic threads used may be of any suitable substances. Also, in place of the elastic threads, other means for securing elements together to allow flexibility may be substituted as, for example, a light spiral or other form of spring may be incorporated in the base 1 or in the lower part of separators 5, or both, to give a similar effect. The impervious sheets 2 and 13 may be omitted or equivalents substituted therefor.

The shape of the separators may be other than that shown and any form thereof adaptable for the purpose may be used. It is not necessary in all cases that the rubber bands or the like be secured by knotting but it may be cemented onto either the base or the separator, or both. In some cases the rubber bands may be entirely omitted and there may be provided slits in the base and the separators may have thin or neck portions which can be introduced into the slits to hold the separators in position.

Although the specification refers to soft spongy material for the separators, such material need not be sponge rubber or the like but any material of sufficient softness or flexibility, such as cloth, felt, compositions or the like may be used in place thereof and all these materials are included in the terms used herein. The device with or without some slight modification may be used to separate the fingers of the hand for special purposes, as for example, when applying nail polish to the fingers, and in the claims, the reference to a toe separating device is intended to include also a device for separating the fingers of the hand.

These and other changes in the details of the physical structure of the device may be made within the principles herein set forth and the invention is therefore to be broadly construed and not to be limited except by the character of the claims appended hereto.

I claim:

1. A toe separating device comprising a base of a flat member adapted to be placed below the toes of the user, a plurality of upstanding separators mounted on said base, said separators being separate elements and being spaced apart to approximately correspond with the spaces between the toes and adapted to enter into said spaces, said separators being mounted on said base for movement relative thereto by elastic threads passing through said separators and allowing both vertical and horizontal relative movement of said separators.

2. A toe separating device comprising a base of a flat member adapted to be placed below the toes of the user, a plurality of upstanding separators mounted on said base, said separators being separate elements and being spaced apart to approximately correspond with the spaces between the toes and adapted to enter into said spaces, said separators being mounted on said base for movement relative thereto by elastic threads passing through the body of said separators and anchored in said base, thus allowing both vertical and horizontal relative movement of said separators.

3. A toe separating device comprising a base of a flat member adapted to be placed below the toes of the user, a plurality of upstanding separators mounted on said base, said separators being separate elements and being spaced apart to approximately correspond with the spaces between the toes and adapted to enter into said spaces, said separators being mounted on said base for movement relative thereto by elastic threads passing through the body of said separators and anchored in said base, thus allowing both vertical and horizontal relative movement of said separators, said base consisting of a thin, flexible, tough bottom layer and a soft, spongy upper layer attached thereto, said threads passing through said layers and anchored to said bottom layer.

4. A toe separating device comprising a base of a flat member adapted to be placed below the toes of the user, a plurality of upstanding separators mounted on said base, said separators being separate elements and being spaced apart to approximately correspond with the spaces between the toes and adapted to enter into said spaces, said separators being mounted on said base for movement relative thereto by elastic threads allowing both vertical and horizontal relative movement of said separators, a thin, flexible, tough material attached to the lower side of said separators and a similar bottom layer at-

tached to said base, said threads being anchored to both of said thin, flexible, tough materials.

5. A toe separating device comprising a base of a substantially flat member adapted to be placed below the toes of the user, a plurality of upstanding separators mounted on said base, said separators being separate elements and being spaced apart to approximately correspond with the spaces between the toes and adapted to enter into said spaces, said separators having depending anchoring means at the lower end thereof, said base having a plurality of openings, said anchoring means passing through said openings, the lower end of said means being anchored on the under side of said base, said means allowing relative movement of said separators.
